DOZIER FINLEY, OF BERKELEY, CALIFORNIA, ASSIGNOR TO THE PARAFFINE COMPANIES, INC., OF SAN FRANCISCO, CALIFORNIA, A CORPORATION OF CALIFORNIA.

STRIP SHINGLE.

Application filed June 20, 1923. Serial No. 646,572.

To all whom it may concern:

Be it known that I, DOZIER FINLEY, a citizen of the United States, and a resident of Berkeley, county of Alameda, and State of California, have invented a new and useful Strip Shingle, of which the following is a specification.

The invention relates to strip shingles or roofing strips and one of the objects of the invention is the production of a unit of this kind having the greatest possible latitude in its adaptation to ornamental and architectural effects.

Another object of the invention is the production of a strip shingle which may be laid to give a close simulation of a roof formed of wooden shingles.

Another object of the invention is the production of a strip shingle which is so designed that the eye cannot readily identify the shingle-like tabs which form part of any one strip.

Another object of the invention is the production of a strip shingle possessed of great ornamental possibilities, and which is at the same time economical, in that the smallest possible amount of roofing material is used in proportion to the exposed surface of the shingles.

Other objects of the invention, together with the foregoing, will be set forth in the following description of the preferred embodiment of means for practicing the invention, and which is illustrated in the drawings accompanying and forming part of the specification. It is to be understood that I do not limit myself to the showing made by the said description and drawings, as I may adopt variations of my preferred form within the scope of my invention as set forth in the claims.

Referring to the drawings:

Figure 1 is a plan view of my roofing strip.

Figure 2 is a plan view of a strip of roofing material out of which my shingles are formed and showing how the shingles are cut relative to the strips.

Figure 3 is a plan view of a section of roof formed with my shingles.

Figures 4 and 5 are plan views of modified forms of my shingle strip, and illustrate the possibility of varying sizes in the individual shingle tabs without varying the

overall size and without departing from dimensions which will permit all of the shingles to be laid together in the same area of roofing.

There is an increasing demand for roofing shingles having a variation of color and with which roofs of artistic value may be laid. Variation of color, however, is of little value from an artistic viewpoint if the shingles are of a geometrically repetitional shape and are laid down in a checker-board pattern. In strip shingles heretofore known it is impossible to secure variations of colors which will be haphazard in the coloring of the individual tabs of the strips when the shingles are laid in place. If the strip shingles consist of four exposed tabs, a roof laid to give color variation will show four tabs of one color in line and four tabs of another color in line, and four tabs of still another color also in line, and so on indefinitely, that is the roof is divided into groups of four tabs each and the eye can analyze this arrangement and classify the effort of the designer as a cheap attempt at ornamentation.

Forms of strip shingles heretofore proposed have been characterized by a rigid adherence to the principle that the tabs of such shingles must be of the same geometrical shape and size. This results in checker-board or at least a geometrical effect when such shingles strips are laid, and while this effect is in some degree alleviated by the use of different colors for alternate rows and by the laying of alternating rows of strips in reverse position, such roofs always retain the appearance of mechanical regularity. The irregularity of width of the wooden shingle, and the variation of color which characterizes it because of the varying texture of the wood, are the basic reasons for its selection in securing certain artistic and architectural results, which it has been impossible to obtain by any other means. My invention is directed to supplying in a strip shingle means for attaining the same, or at least comparable results.

It will be understood that if the tabs in any one shingle strip are all of a single color and shape, it is impossible for a strip to be laid out so that the tabs will not fall into groups of three, four or five tabs in line and of the same color. I have, therefore, sought in my strip shingle to make the ex-

posed tabs of any one strip fall so far as possible into two or more different rows when the strip is laid. I have also sought to make tabs of varying sizes and to interrupt or break the serial continuity of more than two shingle tabs of the same color in one line. In the present invention I have so far accomplished these ends as to make the tabs of each strip fall into two rows and 10 in no case are more than two shingle tabs of a strip brought into a side by side position. The effect is such that the eye does not analyze the system by which the tabs are positioned without long study and the eye 15 does not even classify the connection between the tabs of any one strip when there is an extremely wide variation of color in the different strips. For this reason a roof of 20 my strip shingles in which there is a wide variation of color will appear to be made with individual shingles of varying color and size placed haphazard.

In terms of broad inclusion, my strip shingle comprises a strip of roofing material 25 basically rectangular in form and having recesses in one of the long sides which form shingle-like tabs. One of these tabs extends beyond the confines of the basic rectangle so that when the shingle strip is laid the extended tab forms part of the next lower course. One of the recesses is somewhat wider than the extended tabs and provides an apparent interruption in the continuity 30 of the row of tabs in which is laid the extended tab of the shingle strip next above. Preferably the recesses are so spaced that the shingle tabs formed thereby vary in width.

In Figure 1, I have shown a plan view of 40 a strip shingle embodying my invention. The dimensions of the several parts of the strip shingle are also indicated, tho not in any way as a limitation because it is obvious that these are subject to wide variation. The dimensions, however, will indicate the general proportions existing between the parts and define a size which I have found to be very satisfactory and one 45 economically obtained from a strip of roofing material forty inches wide. The method of cutting these shingles from a strip of roofing material is indicated in Figure 2, and it will be noted that the design is such as to be substantially without waste, such 50 waste being confined to the material from the recesses 7. The strip shingle, as shown in Figure 1, is principally confined within a basically rectangular outline. Slots or recesses 7 preferably of a width comparable 55 with that usually existing between wooden shingles in a row or course are formed in one of the long sides of the rectangle. The spacing of these recesses from the ends of the strip is such as to form tabs 8, 9 and 10 of different width, and the depth of the re-

cesses, which determines the length of the tabs 9 and 10, is that amount which it is desired to expose the strip to the weather, and in the present instance may be assumed to be 4 inches. The end tab 8 is extended beyond the confines of the basic rectangle an additional four inches, that is for an amount sufficient to bring the end of it coincident with the edge of the next lower course of tabs when the shingle strips are 75 laid. Also formed in the same side of the shingle strips is a wide recess 12 of the same depth as the recess 7 and preferably a bit wider than the tab 8. This recess leaves the shingle-like tab 13 to complete the series of 80 tabs formed on the shingle strip, and provides an apparent interruption in their continuity.

The second and third tabs 9 and 10 respectively are interchangeable as to width. It is preferred to make a portion of any lot of shingle strips with the tabs 9 and 10 of the widths indicated in Figure 1, and another portion of the lot in which these dimensions are reversed, but in all cases to keep the sum of their respective widths 16 inches. This variation is shown in Figure 4 and indicated by the dimensions in circles in Figure 1. It will be noted that in the method of cutting the strip shingle illustrated in Figure 2, one-half of the number are formed as shown in Figure 1 and one-half as shown in Figure 4, that is with the dimensions of tabs 9 and 10 reversed. Of course, the particular dimensions may be departed from, or even five tabs may be used in place of those described, as shown in Figure 5, in which the right hand tab is split into two tabs 14 and 15. I have found, however, that the variation of the two tabs 9 and 10, together with all 100 of the other elusive variations in the strip, is sufficient to accomplish the purpose of my invention.

In laying the shingle strips, nails are driven through the shingles into the roof deck preferably above the upper, or up-roof and of each of the slots or recesses 7, above the middle portion of the tab 13 and in the middle of tab 8 just within the basic rectangle. The position of the nails is indicated by crosses 16 in Figure 1. It will be seen that all nails so placed, are in such position as to be covered by the overlying shingle tabs.

In Figure 3, I have shown a portion of 110 a roof formed by my shingle strip. Strips of the above described character and with the variation shown in Figures 1 and 4, are laid in successive rows of four inches exposure to the weather each, building up 115 from eave to ridge. For a shingle strip having the dimensions indicated in Figure 1, the right end of each strip over-lies the left end of the next shingle strip in the row, a distance of four inches, and each shingle 120

strip is offset with relation to the next lower one, a distance of $8\frac{1}{4}$ inches to the left. When so laid the extended tab 8 of a given strip lies within the recess 12 of one of the 5 underlying strips. Thus an exposed tab of each shingle extends down-roof into a row of shingles below that in which the remainder of its exposed tabs are positioned, and in turn the continuity of the remaining tabs 10 is broken by the interposition among them of an exposed portion of a long tab from a strip in the row above. Thus with shingle strips of two or three varying shades laid haphazard, the otherwise geometrical effect 15 of the exposed shingle-like tabs, is so broken up as to prevent ready analysis of the system of laying. This gives an effect heretofore found impossible to obtain with strip shingles, and one associated only with the 20 use of wooden shingles.

By lapping the ends of the strips as described, there is produced a raised place, or hump, at intervals in each row. This is not objectionable in a roof such as is obtained by 25 the use of my shingle strips, and rather contributes to a desirable departure from the flatness and mechanical exactness which characterizes shingle strip coverings of prepared roofing of the type heretofore in use.

30 I claim:

1. A roofing strip comprising a series of shingle-like rectangular tabs, one of said tabs extending beyond the others.
2. A roofing strip comprising a basically 35 rectangular piece of roofing material having recesses in one of the long sides thereof to form shingle-like tabs, one of said tabs being extended beyond the rectangular base,

and one of said recesses being wider than the others.

3. A roofing strip comprising a series of shingle-like tabs, one of said tabs extending beyond the others, and two of said tabs being separated by a space wider than said extended tab.

4. A roofing strip comprising a basically rectangular piece of roofing material having recesses in one of the long sides thereof to form shingle-like tabs, the tab on one end being extended beyond the rectangular base, and the other tabs being of equal length.

5. A shingle strip comprising a basically rectangular piece of roofing material having a recess in one of the long sides thereof to provide an apparent interruption in one course of shingles, and an extended tab on said piece adapted to fill the recess in the next course below.

6. A roof comprising courses of shingle strips, the main body of each strip having shingle-like tabs of unequal width formed thereon by recesses in the edge thereof, and each strip having a shingle-like tab forming a part of the next lower course.

7. A roof comprising courses of shingle strips, the main body of each strip having shingle-like tabs formed thereon and having a recess providing an apparent interruption in the course, and a shingle-like tab extended from each strip to fill the recess in the strip below.

In testimony whereof, I have hereunto set my hand.

DOZIER FINLEY.
